Patented July 6, 1976

240,401

AEROSOL DISPENSER

John C. Armstrong, 1031 Canton Ave.,
Milton, Mass. 02186

Filed June 10, 1974, Ser. No. 477,662

Term of patent 14 years

Int. Cl. D9—01

U.S. Cl. D9—23

FIG.1

FIG.2

FIG.3

FIG.4

FIG.5

FIG. 1 is a front elevational view of an aerosol dispenser, showing my new design;

FIG. 2 is a side elevational view;

FIG. 3 is an exploded front elevational view;

FIG. 4 is a top plan view; and

FIG. 5 is a bottom plan view.

The dispensing nozzle is conventionally recessed and the rear of the actuator or pump is the same as the front but without the nozzle element.

I claim:

The ornamental design for an aerosol dispenser, as shown and described.
